an elongated slot 62 formed therein, as perceived in Figure 4 of the drawings. Thus, rotation of the arm 50, through the wheel 56, moves the block 60 and the pin 30. Movement of the pin 30 effects a corresponding movement of the jaw 24.

In operation, the first pivot point 16 serves as the axis of the levers. When the levers are moved apart, the pivot 16 drops and conversely moves upwardly when the levers are pressed together. When an intermediate position is assumed by the pivot, the pressure on the levers is balanced and no grip pressure is required to maintain the jaw pressure. This allows the levers to be pressed together with the sections 18 and 20 abutting and yet keeps the correct pressure on the jaws.

A modified form of jaw is provided in Figure 3 of the drawings, wherein the wrench 10 is adaptable for use as a wire cutter. The cooperating gripping faces of the jaws 24 and 26 are triangularly projected to receive and accommodate cutting blades 64 and 66 detachably secured on the faces. The cutting blades, for cutting bolts or the like, are held on the gripping portions of the jaws, through the medium of spring steel clamping arms 68, which project from the blades. The arms 68 are formed with inwardly directed detents 70, which are adapted to be received within recesses 72 formed in the sides of the jaws 24 and 26, adjacent the face portion thereof.

Thus, there is provided a compact and efficient and adjustable locking wrench, which will serve many utilitarian purposes, due to the angular adjustment, which may be effected on the jaws, as a unit and relative to each other.

However, many other purposes and objects of this invention will become apparent to those skilled in the art, upon a perusal of the foregoing description, in view of the accompanying drawings, and it is understood that certain changes may be effected therein, within the spirit of the invention and scope of the appended claims.

Having described the invention, what is claimed as new is:

1. An adjustable work handling tool comprising a first and a second lever, a first pivot connecting said levers to each other adjacent one end thereof, a first rigid jaw member, a second pivot connecting said first jaw member to said first lever adjacent the pivoted end thereof, a second rigid jaw member, a third pivot connecting said second jaw member to said second lever adjacent the pivoted end thereof, a fourth pivot connecting said first and second jaw members to each other intermediate the ends thereof, means carried by said levers limiting closing movement thereof, said third pivot being laterally offset towards the handle portion of said second lever from the line defined by said first and second pivots when said levers are in their closed position, means carried by said second lever for adjustably moving said third pivot towards and away from said first pivot.

2. An adjustable work handling tool comprising a first and a second lever, a first pivot connecting said levers to each other adjacent one end thereof, a first rigid jaw member, a second pivot connecting said first jaw member to said first lever adjacent the pivoted end thereof, a second rigid jaw member, a third pivot connecting said second jaw member to said second lever adjacent the pivoted end thereof, a fourth pivot connecting said first and second jaw members to each other intermediate the ends thereof, means carried by said levers limiting closing movement

thereof, said third pivot being laterally offset towards the handle portion of said second lever from the line defined by said first and second pivots when said levers are in their closed position, means carried by said second lever for adjustably moving said third pivot in a path parallel to a line extending radially of said first pivot.

3. An adjustable work handling tool comprising a first and a second lever, a first pivot connecting said levers to each other adjacent one end thereof, a first rigid jaw member, a second pivot connecting said first jaw member to said first lever adjacent the pivoted end thereof, a second rigid jaw member, a third pivot connecting said second jaw member to said second lever adjacent the pivoted end thereof, a fourth pivot connecting said first and second jaw members to each other, intermediate the ends thereof, said second jaw member having an elongated slot therein, said third pivot being longitudinally adjustably received in said slot whereby the angular portion of said jaw members as a unit may be varied relative to said levers.

4. An adjustable work handling tool comprising a first and a second lever, a first pivot connecting said levers to each other adjacent one end thereof, a first rigid jaw member, a second pivot connecting said first jaw member to said first lever adjacent the pivoted end thereof, a second rigid jaw member, a third pivot connecting said second jaw member to said second lever adjacent the pivoted end thereof, a fourth pivot connecting said first and second jaw members to each other intermediate the ends thereof, a lead screw carried by said second lever and extending transversely of said first pivot, a follower carried by said lead screw, said third pivot being carried by said follower.

5. An adjustable work handling tool comprising a first and a second lever, a first pivot connecting said levers to each other adjacent one end thereof, a first rigid jaw member, a second pivot connecting said first jaw member to said first lever adjacent the pivoted end thereof, a second rigid jaw member, a third pivot connecting said second jaw member to said second lever adjacent the pivoted end thereof, a fourth pivot connecting said first and second jaw members to each other intermediate the ends thereof, means carried by said levers limiting closing movement thereof, said third pivot being laterally offset towards the handle portion of said second lever from the line defined by said first and second pivots when said levers are in their closed position, a lead screw carried by said second lever and extending transversely of said first pivot, a follower carried by said lead screw, said third pivot being carried by said follower.
